UNITED STATES PATENT OFFICE.

WALTER NOWAK, OF BUFFALO, NEW YORK.

SAFETY RAZOR.

1,403,562.

Specification of Letters Patent. Patented Jan. 17, 1922.

Application filed January 22, 1921. Serial No. 439,148.

To all whom it may concern:

Be it known that I, WALTER NOWAK, a citizen of the United States, and a resident of Buffalo, in the county of Erie and State 5 of New York, have invented certain new and useful Improvements in Safety Razors, of which the following is a specification.

My present invention relates generally to safety razors and more particularly to that 10 type of safety razor employing double edged blades clamped upon the outer convex face of a guard plate and between this guard plate and a clamping plate, my object being the provision of certain novel connections 15 whereby the clamping plate may be secured in connection with the guard plate in such manner as to permit of its ready association therewith and disassociation therefrom.

In the accompanying drawing which illustrates 20 my present invention and forms a part of this specification,

Figure 1 is a perspective view of my improved safety razor complete.

Figure 2 is a sectional view thereof, the 25 section being taken lengthwise through the head,

Figure 3 is a detail perspective view of the clamping plate removed,

Figure 4 is a similar view of the guard 30 plate with its handle, and

Figure 5 is another similar view of one of the blades.

Referring now to these figures my invention proposes a safety razor including a 35 handle 10 in rigid connection with one end of which is a guard plate 11 having an outer convex face turned away from the handle, this guard plate being provided with apertures 12 adjacent to its opposite ends, in line 40 with its longitudinal axis, and also in line with end lugs 13, which latter are curved and deflected rearwardly toward and upon opposite sides of the handle 10 and are provided with terminal engaging edges 14 for 45 a purpose which will be presently described.

The guard plate is also provided along its longitudinal side edges with the usual guard fingers 15 adapting the same for co-operation with the cutting edges 16 of a 50 blade 17 such as shown in Figure 5, whose ends have central recesses 18 to register with the openings 12 of the guard plate when the double edged blade is disposed upon the outer convex surface of the guard plate.

55 The clamping plate 19 shown particularly in Figure 3 is also curved in cross section

and its function is to clamp the blade 17 firmly and uniformly upon the outer surface of the guard plate 11, the blade flexing for this purpose as is usual, and this clamping plate in accordance with my invention has integrally struck up and rearwardly projecting tongues 20 at its opposite ends, whose laterally and outwardly offset extremities 21 have bosses 22 adjacent to the shoulder or offset, adapted for engagement by the inner engaging edges 14 of the guard plate lugs 13.

To the above end, association of the parts in operative relation involves the disposition of the blade 17 upon the outer face of the guard plate 11 so that its end recesses 18 register with the guard plate openings 12. The tongues 20 of the clamping plate 19 are then pressed slightly toward one another 75 against their natural spring tension in order that their free offset ends 21 can be shifted rearwardly through the recesses 18 of the blade and the openings 12 of the guard plate so that when the clamping plate 19 is 80 pressed firmly against the blade and the latter thus firmly and uniformly clamped against the outer surface or blade seat of the guard plate to the position shown in Figures 1 and 2, the inner offset ends of the tongues 85 13 of the guard plate and the free engaging edges 14 of the latter will engage the bosses 22 and thus effectively clasp the clamping plate in effective position. 90

This effective position will be retained until the operator grasps the rear free ends of the tongues 20 and presses the same toward one another against their natural spring tension and free of the engaging edges 14 of 95 lugs 13 upon which the natural tension of the normally flat blade 17 will spring the clamping plate 19 forwardly away from the guard plate in order that it may be grasped and pulled entirely free for ready removal 100 of the blade.

My invention thus presents an arrangement by means of which the blade may be readily clamped and immovably held without the use of additional positioning pins 105 and apertures, and by the simple provision of end recesses in the blade which leave the latter particularly strong and durable, impairing as they do to a minimum extent the natural strength of the metal. The 110 clamping means proposed by my invention permit of ready association and disassocia-

tion of the parts, present a neat compact appearance without interfering in any way with proper manipulation of the razor in use, and coact in the formation of a strong and durable structure which avoids threaded parts as well as others of a like nature susceptible of ready wear.

I claim:

1. In a safety razor, a guard plate having 10 a convex blade seating surface and having openings therethrough and rearwardly projecting end extensions forming clasping lugs whose effective ends are spaced rearwardly beyond said openings, a blade having end recesses to register with the guard plate openings, and a clamping plate having rearwardly projecting tongues shiftable through the blade recesses and the openings of the

guard plate and provided with means movable into clasping engagement with the 20 rear effective ends of the lugs of the guard plate as described.

2. In a safety razor, a guard plate and blade thereon having registering cutout portions, said guard plate having rearwardly 25 projecting and inwardly inclined end lugs whose rear effective ends are aligned with and spaced rearwardly from the guard plate cutout portions and a clamping plate for holding the blade in place, having projecting 30 resilient tongues insertable through the cutout portions and shiftable into clasping relation with the rear effective ends of said lugs as described.

WALTER NOWAK.
